UNITED STATES PATENT OFFICE.

CALVIN E. CADMAN, OF SOUTH BELOIT, WISCONSIN.

GRINDING-WHEEL CHUCK.

1,389,738.

Specification of Letters Patent. Patented Sept. 6, 1921.

Application filed July 19, 1920. Serial No. 397,193.

To all whom it may concern:

Be it known that I, CALVIN E. CADMAN, a citizen of the United States, residing at South Beloit, in the county of Winnebago and State of Wisconsin, have invented certain new and useful Improvements in Grinding-Wheel Chucks, of which the following is a specification.

This invention relates in general to grinding wheels, and has more particular reference to the chuck in which such wheels are mounted.

It has heretofore been customary in mounting these grinding wheels in chuck bodies to retain them in position by holding means which engage the perimeter of the wheel at spaced intervals only. In such constructions, however, the spaced holding means have a tendency to cut into the surface of the grinding wheel, permitting the wheel to work loose, and furthermore, such a series of engaging points tended to weaken the wheel and render it liable to split or fracture.

One of the primary purposes of my present invention is to provide a holding chuck for grinding wheels of this character, in which the wheel holding or clamping means shall be so constructed that it will engage and clamp the grinding wheel substantially throughout its entire periphery, thus obviating the objections above mentioned.

Another object of my invention is to provide a grinding wheel chuck which will be simple in construction, cheap to manufacture, and durable in operation, and one which will securely hold the grinding wheel in position without danger of its working loose.

A further feature of my invention resides in the provision of spacing means capable of insertion behind a grinding wheel for the purpose of projecting the face of the wheel beyond the chuck after the wheel has been partially worn down.

Other objects and advantages of this invention will be readily understood and appreciated from the following description, when considered in connection with the accompanying drawings.

Referring to the drawings:

Figure 1 is a diametral sectional view of a grinding wheel chuck embodying my invention;

Fig. 2 is a similar view showing the appli-

cation of my improved spacing ring thereto; and

Fig. 3 is a face view partially in section, of the chuck, shown in Fig. 2.

By reference to the drawings, it will be observed that the chuck consists primarily of a body, consisting of a disk 5 and an axial flange 6 formed around the perimeter of the disk. This body is provided with the usual central opening 7 adapted to accommodate the end of a shaft upon which the chuck is mounted, and a plurality of surrounding holes 8 adapted to receive the screws or bolts by which the chuck is secured to its supporting shaft.

The flange 6 of the body is preferably thickened near its margin, as indicated by reference character 9, and this thickened portion is provided with an internal groove 11 adapted to accommodate the clamping ring 12. This ring or gib preferably consists of a piece of cold rolled steel bent into substantially circular form and sprung into position in the groove. The ring, as will be understood, is split, that is, it is non-continuous, and for the purpose of preventing rotation of the ring within the chuck body, I prefer to equip the body with an inwardly projecting stud or pin 13 extending into the groove 11 between the opposed ends 14 of the ring. Rotation of the ring within the chuck body is prevented by this pin.

The chuck body may be made of any desired size adapted to accommodate the grinding wheel proper, which is made of abrasive material and is adapted to fit loosely within the body. The grinding wheel is indicated by reference character 15 in Fig. 1, this wheel being of full size and of the relative thickness of a new wheel. After the wheel has been worn down approximately to the outer edge of the body flange 6, it may be removed and re-positioned, as shown in Fig. 2, the wheel being spaced from the disk 5 by a spacing ring 10, preferably of angular shape in cross section to afford a surface of substantial area against which the inner face of the wheel may abut. When the grinding wheel has again been worn down, a thicker spacing ring may be substituted for the ring 16, and in this manner practically the entire body of the grinding wheel may be used up before a new wheel is required.

At regularly spaced intervals around its

circumference, the body flange 6 is provided with tapped openings intersecting the groove 11, into each of which is threaded a set screw 16, and after the grinding wheel has 5 been positioned in the body, it is clamped therein by threading these set screws inwardly against the clamping ring 14 so as to compress this ring into tight clamping engagement with the perimeter of the grinding 10 wheel. It will be observed that this clamping ring under the action of the set screws 16, engages the periphery of the grinding wheel at substantially all points in its circumference so that the wheel is firmly 15 clamped and held throughout its entire periphery instead of being gripped at a series of spaced intervals, as has heretofore been customary. The clamping ring, being of substantial width, does not penetrate the 20 body of the wheel as a series of narrow clamping devices would, and consequently, the wheel cannot work loose, nor is there any tendency toward splitting of the wheel as the result of the clamping action. When 25 it becomes necessary to reset the wheel in the chuck or to replace it by another, this can be readily accomplished by simply loosening the set screws 16, whereupon the clamping ring will expand away from the 30 perimeter of the grinding wheel, permitting the wheel to be removed and repositioned or replaced by another, as occasion may require.

It is believed that my invention, its construction, and mode of operation will be 35 understood from the foregoing without further description, and while I have shown and described a preferred embodiment thereof, it should be manifest that the details of construction are capable of considerable 40 modification and variation without departing from the spirit of the invention, as set forth in the appended claims.

I claim:

1. A grinding wheel chuck, comprising a 45 body adapted to receive a grinding wheel, said body being provided with an internal

groove, a split ring disposed in said groove, and means acting on said ring for forcing the same into clamping relation with the perimeter of a grinding wheel disposed within 50 said body.

2. A grinding wheel chuck, comprising a body including a peripheral axially disposed flange provided with an internal groove, a clamping ring positioned in said groove, 55 and a plurality of set screws carried by said body and adapted to force said ring into clamping engagement with a grinding wheel disposed within said body.

3. A grinding wheel chuck, comprising a 60 body including an axially disposed flange provided with an internal groove, a split ring seated in said groove, means for preventing rotation of said ring relatively to the body, and a series of set screws arranged 65 to act upon said ring.

4. The combination of a chuck body provided with an internal groove, a clamping ring disposed in said groove, means for compressing said clamping ring, a grinding 70 wheel positioned within the body and ring, and a spacing ring disposed between said grinding wheel and said body.

5. A grinding wheel chuck, comprising a body provided with an annular flange 75 adapted to surround a grinding wheel, a compressible ring interposed between said flange and the entire periphery of said wheel, and substantially a series of radially disposed screws threaded through said flange 80 for compressing said ring around and into clamping relation with said wheel.

6. A grinding wheel chuck, comprising a body provided with an annular flange adapted to surround a grinding wheel, a 85 clamping ring interposed between said flange and the perimeter of said wheel, and radially movable means engaging said ring at a plurality of spaced points around the periphery thereof to compress the same into 90 clamping relation with said wheel.

CALVIN E. CADMAN.
